corporation of New York

Application July 27, 1949, Serial No. 4,165

Term of patent 7 years

(Cl. D58—12.6)

To all whom it may concern:

Be it known, that I, Murray S. Skulnik, a citizen of the United States of America, residing in Brooklyn, Kings County, State of New York, have invented a new, original, and ornamental Design for a Box or Similar Article, of which the following is a specification, reference being had to the accompanying drawing, forming a part thereof.

In the drawing:

The side of the box not shown is identical to Figure 3, and the rear of the box is plain.

I claim:

The ornamental design for a box or similar article, substantially as shown and described.
MURRAY S. SKULNIK.
